US00D996985S

(12) **United States Design Patent** (10) **Patent No.:** **US D996,985 S**
Cotter (45) **Date of Patent:** **** Aug. 29, 2023**

(54) **DOUBLE-ENDED MEASURING SPOON SET**

(71) Applicant: **Progressive International Corporation**,
Kent, WA (US)

(72) Inventor: **Jennifer Cotter**, Seattle, WA (US)

(73) Assignee: **Progressive International Corporation**,
Kent, WA (US)

(**) Term: **15 Years**

(21) Appl. No.: **29/727,344**

(22) Filed: **Mar. 10, 2020**

(51) **LOC (14) Cl.** **10-04**

(52) **U.S. Cl.**
USPC **D10/463**

(58) **Field of Classification Search**
USPC D10/462, 463; D24/116; D7/691
CPC B65D 41/26; G01F 19/00-007;
A47G 2019/2277

See application file for complete search history.

(57) **CLAIM**

The ornamental design for a double-ended measuring spoon set, as shown and described.

DESCRIPTION

FIG. 1 is a top perspective view of a double-ended measuring spoon set, showing my new design.

FIG. 2 is a front elevational view of the double-ended measuring spoon set.

FIG. 3 is a top plan view of the double-ended measuring spoon set.

FIG. 4 is a left side elevational view of the double-ended measuring spoon set.

FIG. 5 is a right side elevational view of the double-ended measuring spoon set.

FIG. 6 is a bottom plan view of the double-ended measuring spoon set.

The broken lines depict portions of the article that form no part of the claimed design.

1 Claim, 6 Drawing Sheets
